CALCULATING MACHINE

Robert Severin Nilsson, London, England

Application March 17, 1943, Serial No. 479,520
In Great Britain July 7, 1941

4 Claims. (Cl. 235—79)

This invention relates to a calculating machine of the kind in which there are provided a plurality of coaxial setting-up wheels each furnished with elements having teeth which normally are retracted and are adapted to be extended outward on the actuation of key elements in order to cause any number of such teeth corresponding with the number indicated upon a particular key to project so that they may co-operate with toothed wheels associated with a counter mechanism so as to cause the counter discs of such mechanism to be displaced in varying degrees in accordance with the number of teeth so caused to project and in which the coaxial setting-up wheels are mounted on a carriage to which translatory motion in a stepwise manner is imparted in order to bring them into position to effect the operation of the counter discs.

According to the invention the setting-up wheels are furnished with rigid elements each toothed at one end, the end opposite to the toothed end being arranged to co-operate directly with bars operated upon by the key elements.

Further features of the invention are pointed out in the claims.

The invention will be described further in detail and by way of example with reference to the accompanying drawings in which:

Figure 1 is a transverse sectional view of a machine according to the invention, more or less diagrammatic, and showing sufficient parts to explain the invention;

Figure 2 is a plan view of the keys and the bars operated thereby;

Figure 3 is a view looking from the right of Figure 2;

Figures 4, 4a, 4b, 4c, and 4d are fragmentary views illustrating certain details in connection with the key arrangement;

Figure 5 is a side elevation of one of the setting-up wheels;

Figure 6 is a section taken on the line VI—VI of Figure 5;

Figure 7 is an elevation similar to Figure 5, but with the front plate removed to expose the rigid toothed elements.

Referring first to the general construction and arrangement seen in Figure 1, a pair of horizontal guides 2 are fixedly mounted across the machine on which can slide the carriage 3 containing a plurality of side-by-side setting-up wheels, the construction of which is more clearly seen in Figures 5, 6 and 7. In Figure 1 the end

one of this series of setting-up wheels will be identified by the reference numeral 10 applied to one of its side plates. The carriage 3 with its setting-up wheels is advanced step-by-step across the machine from right to left, upon operation of keys 24 by escapement mechanism (not shown) as known in this kind of machine, and when the carriage 3 is in the extreme right-hand position, the extreme left-hand setting-up wheel may be operated upon by the keys as explained later, and so on, each setting-up wheel in turn being operated as the carriage advances step-by-step.

The setting-up wheels are strung on a pair of rods 4 by which the several wheels are prevented from relative rotation, but by which, also, the whole assembly of wheels may be rotated together when the machine is operated in any known or suitable manner.

20 The setting-up wheels, by their teeth (which are selectively set up through the key mechanism as hereinafter described), actuate the counter mechanism indicated in Figure 1 by a series of toothed wheels, the end one 90 of which is shown, and by a corresponding series of numeral discs 92 having pinions 91. Suitable mechanism is employed to carry the tens from one numeral disc to the next succeeding one, this forming no part of the present invention, but 25 such a mechanism is generally illustrated by the arm 93 which is one of a plurality furnished at their respective inner extremities with cam surfaces 94, the arms being individually constrained by springs 95 to assume one of two definite positions. The cam surface 94 co-operates with one of the elements 96 which slide in slots in a pair of discs 99 keyed on the shaft 100. In brief, the sliding action of the particular element 96 is originated by a pin 101 on a numeral disc 92 engaging a further cam surface 102 on an arm 93, moving the latter into the path of a projection 103 of the element 96, and this slides the element into a position where the projection 103 will engage between the teeth of one of the 30 tooth wheels 90 so that it is moved a step and turns the pinion 91 of the next adjacent numeral disc 92.

35 The parts indicated by the reference numerals 111, 112, 113, 115, 117 and 124 diagrammatically represent elements of a mechanism with which the present invention is not concerned, associated with means for actuating a revolution counter device for indicating multipliers or quotients in the solution of problems involving multiplication or division respectively.

Referring now to the essential features of the invention, and firstly to the construction of the setting-up wheels, each of these comprises a pair of side plates 10 between which are mounted four rigid elements 11, 11a, 11b, and 11c, having teeth at one end (uppermost in Figure 7), and these elements are slidable and appropriately guided between the side plates. The toothed elements 11-11c are normally held in their retracted position by means of a spring 13 10 bearing on abutments 14 provided adjacent to what are normally their lower extremities.

The number of teeth provided by these elements differs. Thus, it will be seen that the element 11 has one tooth, the element 11a three teeth, the element 11b three teeth and the element 11c two teeth, so that each actuating wheel may be caused to present any number of teeth from 0 to 9 to the toothed wheels in the counting mechanism for as will be appreciated if the element 11 alone is extended only one such tooth will be presented, whereas if the element 11c is actuated alone, two teeth will be presented, while if either of the elements 11a or 11b is actuated, three teeth will be presented and by the combined actuation of 11 and 11a four teeth, 11a and 11c five teeth, 11a and 11b six teeth, 11, 11a and 11b seven teeth, 11a, 11b, 11c eight teeth and 11, 11a, 11b, 11c nine teeth.

Each of the elements 11, 11a, 11b, 11c is provided with a lateral extension 15 furnished with a cam surface cooperating with correspondingly formed cam surfaces 16 on a sector rotatably mounted upon the spindle 17 and furnished with a limb 18 co-operating with a spring 19 whereby it is constrained to assume the position shown in Figure 5. On the sector there is also provided an extension 20.

When the elements 11-11c are advanced, the sector is, under the action of the spring 19, caused to be rotated to engage below the lateral extensions 15 on such of the elements as have been moved into a position to present their toothed ends to the toothed wheels 90 of the counting mechanism, and thus retain the teeth in the projected position until, by the return movement of the carriage 3 when zeroising the extension 20 is brought against a cam 21 which operates to displace the sector, thus permitting the toothed elements 11-11c to be retracted by the spring 13. The sector, after passing the cam, resumes the position shown in Figure 5 and thus secures the toothed elements 11-11c in their retracted position.

The said toothed elements are caused to be projected by the actuation of one or more of four bars 22 mounted on pivots 23. The arrangement of these bars will be seen most clearly from Figures 1, 2, 3 and 4-4d.

For actuating the bars, keys 24 inscribed with the numbers "1" to "9" are provided. The keys are associated with springs 25 and are arranged in three banks in the construction illustrated, and they are furnished on their sides with projections 26 of different form so that as may be seen from Figures 3 and 4 to 4d the requisite bar or plurality of the bars 22 selected by the key may be actuated to cause the number of teeth corresponding with the number inscribed on the particular key depressed, to be extended.

The bars 22, pivoted at 23, and selectively operated as explained according to the particular key selected for depression, directly work on the rigid elements 11-11c of the setting-up wheels. It

will be observed that said key-operated bars are formed at their inward ends with upturned extremities which respectively press directly on the ends of the rigid toothed elements 11-11c at the lower ends of the latter. Thus, upward movement of an inward end of a bar 22 pushes one of the rigid elements 11-11c against the action of its spring 13, and causes the toothed end of the rigid element to move into a position where it can operate the toothed wheel 90 of the counter mechanism. There it is retained and eventually released as aforesaid by the mechanism including mainly the sector on the spindle 17 having its cam surfaces 16 coacting with the cammed extensions 15.

I claim:

1. A calculating machine including a series of toothed wheels for actuating a counter mechanism and numeral discs, and means for actuating said counter mechanism and discs through said wheels, said means comprising, an escapement controlled carriage, spaced longitudinally disposed bars rotatably mounted on said carriage, and a plurality of setting-up wheels supported on said bars in side-by-side non-rotatable relation, said wheels each including a pair of side plates, rigid toothed elements slidably guided between said plates, said elements each having a different number of teeth for selective projection beyond the periphery of the setting-up wheels into operative relation to said toothed wheels, spring means for normally retracting said toothed elements within the circumferential limits of the setting-up wheels, holding means for temporarily maintaining said toothed elements in projected position, means for releasing said holding means, and key levers for engaging the end of said rigid toothed elements opposite the teeth thereon for slidably shifting the same to project the teeth beyond the circumference of the setting-up wheel.

2. A calculating machine, according to claim 1, wherein the holding means for temporarily maintaining the toothed elements in projected position, includes, a lateral extension on each toothed element provided with a cam surface cooperating with cam surfaces on a sector mounted on a side plate, whereby the shifting of a selected toothed element by a key lever moves the sector so that it can engage below said lateral extension to retain the toothed element in its projected position.

3. A calculating machine, according to claim 1, wherein the holding means for temporarily maintaining the toothed elements in projected position, includes, a lateral extension on each toothed element provided with a cam surface cooperating with cam surfaces on a sector mounted on a side plate, said sector being oscillatably mounted on one of the side plates and spring-biased to holding position, said sector being also provided with an extension adapted to be engaged by a cam upon return movement of the carriage during zeroising to disengage the said lateral extension from its cooperating cam surface on the sector.

4. A calculating machine, according to claim 1, wherein the holding means consists of a sector pivotally mounted on a spindle arranged co-axially with the side plates and is provided with cam surfaces adapted for engagement with lateral extensions on a toothed element, said sector being spring-biased to holding position, and an extension on the sector adapted to engage a resetting cam element upon return movement of the carriage during zeroizing.

ROBERT S. NILSSON.
